UNITED STATES PATENT OFFICE.

A. D. PURINTON, OF DOVER, NEW HAMPSHIRE.

HAT-CUSHION.

Specification of Letters Patent No. 28,902, dated June 26, 1860.

To all whom it may concern:

Be it known that I, A. D. PURINTON, of Dover, in the county of Strafford and State of New Hampshire, have invented an Improved Absorbing Hat-Cushion, of which the following is a full, clear, and exact description, reference being had to the accompanying drawings, making part of this specification, in which—

10 Figure 1 is a view of a hat with my improved cushion attached; Fig. 2, the sweat leather which surrounds the inside of the crown of the hat; Fig. 3, my improved cushion which is inserted between the sweat leather and the hat at the front part of it.

15 The sweat leather A (Figs. 1 and 2) which is usually placed inside of the crown of a hat, is intended to prevent the perspiration from the head from penetrating the hat 20 and spoiling its appearance, and also to furnish a smooth and agreeable surface to come in contact with the head of the wearer, particularly at the front part. This leather as 25 usually made and applied is but partially effective in protecting the hat, as it is not waterproof and after being worn a short time is liable to be penetrated by the perspiration which also finds its way over the edge of the leather where it is attached to 30 the rim of the hat at the front part.

The object of my present invention is to 35 protect the hat at the front part (where it is most liable to be injured) from the perspiration which may penetrate the sweat leather, and at the same time to interpose a soft and agreeable substance between the forehead of the wearer, and the hard body of the hat, and this I accomplish without the use of a 40 waterproof medium which would tend to keep the head moist where it comes in contact with the hat. And my invention consists in interposing between the sweat leather and the hat at the front part of it a soft elastic cushion made of wool fur or other 45 material which is slightly felted, and is soft and agreeable to the head, and absorbs any moisture which may penetrate the sweat leather.

That others skilled in the art may understand and use my invention I will proceed to describe the manner in which I have carried out the same.

In the said drawings the hat B, Fig. 1, is furnished with the usual sweat leather A between which and the crown of the hat 55 at the front part is interposed the elastic cushion C (dotted in Fig. 1 and detached and enlarged in Fig. 3). This cushion which is made of any suitable material such as wool fur, &c., which can be felted into 60 a sheet of the proper consistency, is cut of a length to reach nearly half way around the hat, and of a width rather less than that of the leather A. It is then shaved down with a sharp knife so as to taper in thickness 65 from the middle of its length at b toward each end c as shown in Fig. 3. The leather A is cut as shown in Fig. 2 with a sufficient fullness on one edge at the middle of its length as at d to extend over the thick part 70 b of the cushion C, and be attached to the hat.

An elastic cushion constructed and arranged as above described will be an agreeable protection to the head from the pressure 75 of the hat, at the same time that it will serve to absorb any moisture which may penetrate the sweat leather, and thus save the appearance of the hat.

I am aware that two or more thicknesses 80 of a thin pile fabric or velvet have been interposed between the sweat leather and the hat, for the purpose of rendering the latter more easy to the head, but such cushion would fail to accomplish the ends which I 85 have in view, as it is neither sufficiently absorbent nor elastic, at the same time that it affords no means of gradually diminishing the thickness of the cushion from the center to the ends by shaving as may be done with 90 the felt cushion. I therefore lay no claim to such a cushion; but

What I claim as my invention and desire to secure by Letters Patent is—

The elastic felted cushion C interposed 95 between the sweat leather A and the crown of the hat, substantially as described for the purpose specified.

A. D. PURINTON.
